UNITED STATES PATENT OFFICE

JOSEPH V. DESMARAIS, OF NEW BEDFORD, MASSACHUSETTS

WINDOW CONSTRUCTION

Application filed May 21, 1932. Serial No. 612,803.

This invention relates to a window construction, and its object is to provide certain improvements by which a substantially air-tight construction can be obtained in a simple manner without the necessity of using complicated and expensive parts.

A further object is to provide a construction of this kind which will obviate the common difficulty resulting from the binding or sticking of the sash due to dampness and swelling.

A still further object is to provide a simple construction in that type of window in which the window frames may be lowered and tilted inwardly to make the rear surfaces of the glass readily accessible for cleaning.

A still further object is to provide a construction which is applicable either to wood or metal windows and frames and which is capable of fabrication without the use of any complicated or unusual parts.

The accompanying drawings illustrate my invention as applied to constructions made of wood.

In said drawings, which form a part hereof;

Figure 1 is a fragmentary front view of a window construction including my invention;

Figure 2 is a vertical section of the construction shown in Figure 1;

Figure 3 is a horizontal section on the line 3—3 of Figure 2;

Figure 4 is a horizontal section on the line 4—4 of Figure 2;

Figure 5 is an enlarged horizontal section substantially on the line 5—5 of Figure 2;

Figure 6 is an enlarged perspective view showing certain details of my construction;

Figure 7 is a longitudinal view of the inner face of the detachable front bead which I employ;

Figure 8 is an enlarged fragmentary view of the upper end of the front bead;

Figure 9 illustrates a slightly modified form of front bead which may be employed; and

Figure 10 shows a slightly modified arrangement for attaching the front bead to the frame members.

Referring to the drawings in detail, the window frame of my construction comprises side members 10, 10, which, as will be noted, are formed of plain strips or boards of uniform thickness. A sill 11 is secured between the lower ends of the side members 10 and a top member 12 is secured between the upper ends of said side members. A facing or finishing strip 13 is secured to the inner edge 55 of the side members 10 and similar strips 14 may be secured to the rear edges of such members.

Adjacent the rear edge of each of the frame members 10 and secured to the inner 65 face thereof is a rear bead 15, these beads extending from the top to the bottom of the frame.

The outer or upper sash of the window is arranged in front of the beads 15. Such 70 outer sash includes side rails 16, an upper rail 17 and a lower rail 18. Between each of the side rails 16 of the upper sash and the adjacent bead 15, I preferably arrange a resilient strip 19 of metal, the inner edge of 75 which is bent laterally and secured beneath the inner edge of the beads 15. The strips 19 extend downwardly a distance substantially equal to the height of the upper sash, and such strips form a yielding abutment against 80 which the side rails 16 of the upper sash are pressed, and they also serve to make a tight joint between rails 16 and the heads 15.

Between each of the side rails 16 of the upper sash and the adjacent side members 10, 85 I arrange a strip 20. These strips extend from the bottom to the top of the frame and are secured to the frame in the manner illustrated particularly in Figure 5. That is, the strips 20 are not rigidly attached to the 90

frame but are preferably held in place by screws or other suitable fastening device 21 which engage elongated openings 22 in the strips 20. By this arrangement the strips

5 20 are supported for limited movement toward and from the rear beads 15. The upper sash is, of course, arranged between the strips 20 on opposite sides of the frame.

The lower or inner sash of the window includes side rails 24, an upper rail 25 and a lower rail 26. The side rails 24 of the inner or lower sash are arranged to abut against the front edges of the strips 20 heretofore described. In other words, the inner or lower 15 sash 24 is wider than the outer or upper sash to the extent of the thickness of the strips 20.

A front bead 27 is arranged in front of each of the side rails 24 of the inner sash. The front beads 27 are preferably secured to 20 the frame members 10 in a manner which will permit them to be readily detached from the side members 10 of the frame. One form of detachable fastening device which I have found convenient consists of what is commonly known as a "snap fastener" and which includes an eye secured to one of the parts and a projection secured to the other part adapted to snap into the eye. Such form of fastening means is illustrated at 28. A guide pin 29 is secured in each of the front beads 27, and these are adapted to register with openings in the frame members 10 so as to properly guide and locate the beads 27 when they are snapped or fastened into position. 35 Each of the beads 27, at its upper end, is provided with an inclined surface 30 and a tongue 31 which cooperate with complementary portions on a transverse bead 32 extending across the top of the frame. By inserting 40 the tongue 31 into the recess provided therefor in the beads 32 and pressing the lower end of the bead against the corresponding side frame 10, the snap fasteners are engaged which serve to hold the bead firmly in position and at the same time permit its easy removal.

The beads 27 are constructed as illustrated, particularly in Figures 7 and 8. Each comprises a main portion, the under surface of 50 which is cut away or rabbeted to receive a movable portion 27a, and between such portions a plurality of springs 27b are interposed which serve to force the movable portion 27a of the bead outwardly, the two parts 55 being held from separation by any suitable fastening device such as screws 27c.

As shown in Figure 10, the side members 10 may be grooved and beads 27 provided with a tongue fitting in the grooves. The beads 60 may be removably held in the grooves by snap fasteners as above described or in any other suitable manner.

In the form of front bead illustrated in Figure 9 a resilient strip of metal M takes 65 the place of the movable portion 27a here-

tofore described, such metal strip being secured to the inner surface of the bead and being arranged to yieldably press against the side rails 24 of the lower sash.

When the front beads 27 are snapped or 70 fastened in position, it will be understood that the spring pressed portions 27a thereof will bear against the front or inner face of the side rails 24 of the lower sash. The springs in the beads will tend to force the inner sash rearwardly against the strips 20 which in turn are forced rearwardly toward the rear beads 15 of the frame. By this means, all parts of the construction are held in tight engagement so as to effectively prevent the entrance of air. But at the same time, the parts are held yieldably in engagement so that in case of dampness or swelling of the wood there is practically no danger of the sash sticking in the frame or becoming 80 so tight as to prevent raising and lowering of the same.

The upper portions of the strips 20 are preferably provided with a central bead 33 which serves to space the front and rear 90 sashes of the window. The bead 33 extends downwardly a distance substantially equal to the height of the rear sash. In other words, the bead 33 is short enough to permit the upper or rear sash to be withdrawn or tilted 95 forwardly when the upper sash is lowered in the frame. Likewise the lower or inner sash can be tilted forwardly or inwardly when the beads 27 are removed. The position of the sash when thus tilted inwardly is illustrated 100 in dotted lines in Figure 2 of the drawings. By this means access can be easily had to the exterior surface of the windows for cleaning the same.

It is to be understood, of course, that the 105 windows are supported in the usual manner by means of cords 34. In the case of the upper sash, the cords 34 are arranged in rectangular notches in the rear corners of the side rails 16 so as to permit the upper sash 110 to be easily tilted forward when the same has been lowered. In the case of the lower sash, the cords 34 are preferably arranged in grooves in the inner edges of the side rails 24. In each case the cords are preferably secured 115 to the sash by means of pins or screws 35 inserted in the side rails and around which the ends of the cords are looped.

To assist in securing an air-tight construction, a resilient packing 36 is arranged between the lower rail of the upper sash and the upper rail of the lower sash, either or both of the rails being suitably notched to receive such packing. It will be seen that when the front sash is forced rearwardly as heretofore described, the front rail 25 will be pressed toward the rear rail 18 which will tend to compress the packing and thus maintain a tight joint at this point. If desired, a packing 37 may also be placed at the lower inner 130

edge of the lower sash against which the lower rail 26 of the lower sash is adapted to press when the sash is lowered.

It is to be understood that my invention is not limited to the exact details herein described but that the same is capable of various changes and modifications, and that various features and details therein may be modified or omitted without departing from the scope 10 of the same as set forth in the appended claims.

Having thus described the invention, what is claimed as new and desired to be secured by Letters Patent is:

15 1. In a window construction, in combination, a frame having side members, a rear bead adjacent the rear edge of each of said side members, a strip secured to the inner surface of each of said side members in front 20 of said rear beads, said strips being supported for limited movement toward and from said rear beads, an outer or upper window sash arranged in said frame between said strips and slideable up and down in front of 25 said rear beads, an inner or lower window sash arranged between said side members and having the side rails thereof abutting against the front edges of said strips, an inner or front bead in front of said inner sash, 30 said front bead including a part arranged to yieldingly press against said inner sash and thereby press said strips and said outer sash toward said rear bead.

2. A construction as defined in claim 1 having means for removably securing said front bead to the inner surface of said side members of the frame.

3. In a window construction, in combination, a lower or inner sash and an outer or 40 upper sash, a frame in which said sashes are arranged, said sash comprising two side members, a rear bead on each of said members against which said outer sash is adapted to press, a strip arranged on each side of 45 said outer sash between the same and said side members, means for securing said strip to said side members to permit limited lateral movement of the strips, said lower or inner sash being arranged to abut against the front 50 edges of said strips, a front bead on each of said side members for holding said inner sash in place, and yieldable means associated with each of said inner beads for yieldingly pressing against said inner sash to press said strips 55 and rear sash toward said rear beads.

4. A window construction comprising, in combination, a frame having side members, an outer or upper sash arranged between said members, a strip interposed between 60 each vertical side rail of said sash and the adjacent frame member, each of said strips being secured to the adjacent side member for limited lateral movement, rear beads against which said outer sash and said strips 65 are adapted to press, an inner sash arranged

between said side members with the vertical side rails thereof abutting against the front edges of said strips, front beads each having a spring pressed portion bearing against said inner sash for forcing the same rearwardly 70 against said strips and the latter against said rear beads.

5. A window construction comprising, in combination, a frame having vertical side members each having a flat inner surface, a rear bead arranged adjacent the rear edge of each of said members, an outer sash in said frame in front of said beads, a strip arranged between each edge of said outer sash and the inner surface of the adjacent frame members 80 for limited movement toward and from said rear beads, an inner sash arranged between said side members and having the side rails thereof arranged to abut against the inner edges of said strips, a front bead arranged in front of each of the side rails of said inner sash, each of said front beads comprising a portion secured to the adjacent side member of the frame and a portion slideable toward and from the adjacent rail of the 90 inner sash, and spring means for pressing each of said slideable portions against the inner sash.

6. A window construction comprising, in combination, a frame having vertical side members, a vertical rear bead adjacent the rear edge of each of said members, an upper or outer sash in front of said rear beads, a strip arranged between each side rail of said upper sash and the adjacent frame member, 95 said strips being secured to the side members for limited movement toward and from said rear beads, a lower or inner sash in said frame, said inner sash having the side rails thereof arranged to press against the front edges of said strip, a compressible packing material arranged between the lower horizontal rail of said upper sash and the upper horizontal rail of said lower sash, a front bead secured to said frame in front 100 of each side of said lower sash, and yieldable means associated with said front beads for forcing said lower sash toward said upper sash to compress said packing and force said strips and upper sash against said rear beads. 110

7. A window construction comprising, in combination, a frame having vertical side members, a rear sash in said frame, rear beads against which said rear sash abuts, a strip arranged between each side rail of said rear sash and the adjacent side member of the frame, said strips being secured to said side members for limited movement toward and from said rear beads, a center bead secured to each of said strips in front of said rear sash, said center beads being of such length as to permit said rear sash to be tilted forwardly in said frame when such sash is lowered, a front sash in said frame with the vertical side rails thereof abutting against 125 130

the front edges of said strip, said front sash being wider than said rear sash, a front bead secured to said frame members on each side of said front sash, yieldable means associated 5 with said front beads for bearing against said front sash to force the same against said strip and the latter against said rear beads, means for detachably securing said front beads in position, thereby to permit said front 10 sash and rear sash to be tilted forwardly in said frame when said front beads are removed and said rear sash is lowered.

In testimony whereof I hereunto affix my signature.
